HERMAN W. ZIMMERMAN, OF CHICAGO, ILLINOIS, ASSIGNOR TO AUTOMOTIVE MAINTENANCE MACHINERY CO., OF CHICAGO, ILLINOIS, A CORPORATION OF ILLINOIS

TOOL SUPPORTING AND OPERATING FIXTURE

Application filed November 4, 1927. Serial No. 230,974.

My invention relates to a portable tool supporting and operating fixture and has to do particularly with a fixture for supporting and operating cylinder grinding tools.

It is quite usual practice to equip garages for the grinding of the cylinders of automobiles, and other, engines. This grinding is usually done without removing the cylinder block and the character of the mechanism ordinarily employed is such that it is necessary for the operator to hold the grinding tool and its driving mechanism in his hands while standing directly above and over the cylinder to be ground. This practice is time-consuming and expensive and requires considerable skill and places a great burden on the operator because of the necessity of supporting the entire weight of the grinding structure which tends to rapidly tire him and impair his skill. Also, the torque of the tool, which is usually electrically driven, must be borne by the operator, tending to prevent the desired accuracy in grinding. The action of the grinding tool is not uniform and there is danger of it seizing and sticking which results in throwing and injuring the operator in addition to the possibility of injuring the tool.

Various forms of apparatus have been devised in attempts to eliminate the foregoing objectionable features and provide more efficient and economical structure but without success because such previous structures require, among other things, readjustment of the entire structure to each cylinder to be ground, which occasions much delay and additional expense and labor; they are bulky and must be moved about as a unit and not easily and quickly adjustable.

One of the objects of my invention is to provide a highly efficient and comparatively lightweight supporting and operating fixture for overcoming all of the foregoing, and any other, objectionable features in previous cylinder grinding mechanisms, such fixture being very simple in construction and cheap to manufacture.

Another object is to provide a fixture of the above character which is adapted to easily align the grinding tool and cylinder with the

tool driving means, and which is capable of adjustment within itself for completing all of the grinding operations as to all of the cylinders with only one setting or positioning of the fixture as a whole, thereby increasing the speed of operations and very greatly lessening the burdens imposed on such operator. To this end, I provide a separate base part adapted to be securely fastened to the cylinder block and adapted to carry a radial support including compound swinging joint members whereby the tool may be adjusted on a straight line and/or on an arc, and in fact, in all directions over an area exceeding that of the maximum size of the cylinder block to be ground.

A further object is to provide such a fixture which is composed of a plurality of positively acting, but readily detachable, parts or units which may be readily and quickly assembled and disassembled without tiring effort.

Still another object is to reduce the time required for completely grinding a cylinder and to greatly reduce the cost of the cylinder grinding operation.

Additional objects are to provide a grinding or cutting fluid reservoir within one of the supporting standards making the fixture more compact and efficient, such reservoir being in adjustable communication with the cylinder to be ground; to provide for ready adjustment for tools of different sizes and lengths as well as adjustment of the length of the stroke to accommodate the mechanism to all sizes and makes of cylinders; to provide means for manually or mechanically moving the grinding tool back and forth in the cylinder and, in case of use of manual means, which may take the form of a hand-operated lever, I provide means for adjusting the uppermost position of such handle for convenient operation by the operator; to provide a support for the grinding tool driving mechanism which is adapted to receive and carry various types and sizes of such driving mechanism; and to provide a novel form of clamp for simultaneously securing all of the swingable supporting parts in any predetermined position.

Other and further objects and advantages will become apparent as this description progresses and by reference to the drawings which show my invention as applied in the 5 grinding of an engine cylinder and wherein,

Figure 1 is a side elevation partly in section of a structure embodying my invention and applied to a cylinder block shown partly in 10 section;

Figure 2 is a top plan view of the structure shown in Fig. 1, the parts being shown in full lines in one grinding position and in dotted lines in a different grinding position; 15

Figure 3 is a side elevation partly in section of the base of the structure in separated relation;

Figure 4 is an enlarged horizontal section taken on line 4—4 of Fig. 1;

20 Figure 5 is an enlarged separated side elevation view of the tool supporting bracket;

Figure 6 is a front elevation of the structure shown in Fig. 5;

25 Figure 7 is an enlarged side elevation of the radial arm shown in separated relation;

Figure 8 is a horizontal section taken on line 8—8 of Fig. 7;

20 Figure 9 is an enlarged side elevation partly in section of a form of drive mechanism 25 for actuating the tool supporting bracket;

Figure 10 is a front elevation of the structure shown in Fig. 9;

25 Figure 11 is a top plan view of a portion of a cylinder block showing a modified arrangement for clamping the fixture base thereto;

Figure 12 is an end elevation of a portion of the structure shown in Fig. 11; and

40 Figure 13 is a separated perspective view 40 of one of the clamping blocks used for securing the base as shown in Fig. 11.

Referring to the drawings, and particularly to Figs. 1 and 2, the cylinder block 15 may be of a form usually employed in connection 45 with automobiles and may or may not remain attached to the automobile while the cylinders are being ground. Any desired type of grinding tool may be employed, but I have shown and preferably employ a grinding 50 tool 16 having grinding stones 17 carried by radially adjustable supports 18 which are, in turn, carried by a suitable frame having an upwardly projecting cylindrical coupling 19. This coupling 19 is hollow and is provided

55 with rather large and exposed bayonet slots 20 adapted to receive the lateral pins 21 carried in the lower ball-shaped end of the drive shaft 22. With this construction the drive shaft is free to adjust itself vertically and

60 angularly relative to its axis to provide an adjustable and non-binding connection between the driving mechanism and the grinding tool. The driving mechanism which I have shown is a form of a motor-driven drill-operating device 23 which has a coupling 24

similar to the coupling 19 attached to the lower projecting end of the motor shaft, this latter coupling 24 being adapted to receive the adjacent end of the drive shaft 22 in a manner similar to its engagement with the coupling 19. It will be understood that when I refer to "drill-operating device" I include any motive means capable of transmitting rotary motion to the grinding tool 16.

According to my invention, the grinding 75 tool and its driving mechanism are supported and aligned and actuated by a radial and universally adjustable mechanism which I will now describe. The cylinder head (not shown) may be secured in place by a plurality of 80 studs carried by the block 15 or by cap screws, or the like, removable with the head. In adjusting this mechanism to the cylinder block, the cylinder head is, of course, removed, and, if the cylinder is of the form shown in the 85 drawings, only one or two, if any of the head holding studs need be removed. Some cylinder blocks may be of such construction and the cylinders so spaced apart that none of the studs need be removed; and this is true 90 as to any other parts of the cylinder block which may be associated with its upper face surface. In grinding of the cylinders I employ a separate fan-shaped base 25 which is long enough to extend entirely across and be 95 beyond the side edges of the top surface of the cylinder block 15. The flared end of the base provides an additional bearing surface upon the top of the cylinder block, the flared surface next to the adjacent cylinders being 100 shaped to the curvature of the cylinder bores so as to provide a maximum supporting surface without interfering with the grinding operations. This flared surface is provided 105 with a vertical hollow cylindrical portion 26 which will be referred to more in detail hereinafter. This base is provided, near its cylindrical part 26, with oppositely directed 110 slots 27, 27^a and 27^b. The slot 27 adjustably receives one of the cylinder head holding 115 studs 15^a, and it is securely fastened thereto by a nut 15^b; or if cap screws are used for holding the head, a cap screw is passed down through slot 27 to engage the threaded opening 120 in the block provided for it. At the other end of the base, I provide another slot 28 which adjustably receives the adjacent stud (or cap screw) 15^c secured thereto by the nut 15^d. If desired, a stud or cap screw need not 125 be used for securing the latter end of the base, but a U-shaped clamp (not shown) carried by 130 studs or cap screws at opposite ends of the base may be employed; or depending on the construction of the cylinder block and spacing of the studs or cap screws, the base may be secured by passing the studs or screws through the base slots 27^a, 27^b and 28. The base 25 is, preferably, located at or near the central part of the block, but the range of 135 the fixture as a whole is such that, if found de-

sirable, it may be located at an off-center point and even near the end of the block as conditions may require without requiring other than the initial base adjustment.

The vertical cylindrical base part 26 is adapted to fixedly receive a vertical cylindrical bushing 30 which serves as a support for the radial arm 31. This radial arm is provided at one end with a split sleeve 31^a having at the split portion opposed bosses or clamp elements 32 and 33 provided with openings, the opening in the boss 32 being threaded to receive the threaded end of a clamp screw 34. The opposite end of this radial arm is also provided with an integral split sleeve 35 having opposing bosses or clamp elements 36 and 37 adjacent the split portion to also receive the clamp screw 34. This clamp screw is adapted to pass freely through the openings in the bosses 36 and 37 and thence diagonally through a slot in the central part of the radial arm 31 and engage the bosses 32 and 33 as above described, and such clamp screw is provided adjacent the bosses 36 and 37 with an enlarged cylindrical part forming a shoulder having a handle 38, and this shoulder cooperating with the threaded end of the clamp screw serves to draw the split portions of these sleeve parts together. This arrangement facilitates very greatly the assembly and disassembly and swinging adjustments of the operating mechanism, particularly when this is being done by a single operator. It enables him to uniformly adjust these sleeves for effecting the desired swinging movement of the radial arm and its associated parts as well as enabling him to simultaneously clamp these parts in their adjusted position ready for the grinding operation.

The radial arm sleeve 35 is adapted to receive and support the lower end of a hollow vertical and cylindrical post 39. The lower end of this post is closed by a plug 40, or any other suitable means, to provide a reservoir 39^a which carries a supply of kerosene, or other suitable grinding or cutting liquid, to be fed to the cylinder during the grinding operation to keep the grinding stones 17 clean. The top of this post is closed by a cap 41 so that the mechanism may be transported without spilling the lubricant and to prevent loss by evaporation, and otherwise. A valved nipple 62 (Figs. 1 and 4) is carried by the lower bracket 45 and is in communication with the reservoir 39^a. This nipple also carries a flexible conduit 63 which delivers the liquid to the cylinder at a rate dependent upon the adjustment of valve 64.

The drill-operating device 23 is carried by a (Figs. 1, 5 and 6) bracket 42 having a pair of vertically spaced arms 42^a and 42^b terminating in sleeve portions 43 adapted to be passed over and slidably engage the vertical post 39. This bracket 42 is additionally

supported and guided by another cylindrical post 44 which is carried by the post 39 by means of a fixed bracket 45 adjacent the bottom of post 39 and by an adjustable bracket 46 adjacent the top of such post. The arms of the bracket 42 are provided with intermediate sleeve-like portions 42^c and 42^d which slidably receive the vertical post 44 as shown clearly in Figs. 1, 5 and 6. The lower bracket 45 has a collar or sleeve fixed to the post 39 by pin 45^a which serves as a shoulder or stop engaging the upper part of the sleeve 35 to position the post 39 vertically therein. The upper bracket 46 has a reduced sleeve portion 46^a which slidably receives and is guided by the upper part of the post 44, and an adjustable split sleeve portion 46^b which embraces the upper part of the vertical post 39. This sleeve portion 46^b is provided with laterally projecting lips 47 at the split both of which have openings, the opening in boss 48 being threaded to receive the threaded end of the clamp screw 49 (similar to clamp screw 34) for tightening the sleeve in adjusted position upon the post 39.

Springs 50 are attached to the opposite sides of the upper bracket 46 and to the bracket 42 for normally supporting the latter bracket in its raised position when the apparatus is at rest, and also serves to cushion the upward and downward movements of such bracket, respectively.

To reciprocate the bracket 42 and its associated mechanism, I may employ a manually operated control lever 51 which is pivoted at one end to the bracket 46 as at 52 and has a handle 53 at its other end. Intermediate the ends of this lever 51 and, preferably, near its pivoted end, I pivotally attach a connecting link 54 which is also pivotally attached to the lower sleeve 43 of the bracket 42. With this construction, it is obvious that by swinging the lever 51 up and down about its pivot 52, the bracket 42 is caused to reciprocate.

I preferably employ an ordinary form of drill driving and holding device as the means for imparting rotary motion to the grinding tool because this is a common tool used for a great number of other purposes in connection with garage work and which may be found practically in every garage. These devices vary considerably in size and shape, including height and diameter and weight, and I have, therefore, provided a universal mounting for the same, or other similar mechanisms, which may be used. This mounting takes the form of two pair of vertically spaced V-shaped arms 58 (Figs. 5 and 6) extending horizontally in equally spaced relation from the bracket 42 adapted to embrace the device 23. Between these arms and in the vertical supporting wall of the bracket 42 I employ a vertical slot 59 adapted to receive a threaded stem 60 (Fig. 130

- 1) of usual form which engages the rear part of the outer surface of the drill device, and which, in some instances, serves as a handle part. This threaded stem 60 is adapted to receive a lock nut 61 which when drawn up tightly in place secures the cylindrical drill device against and within the V-shaped arms 58 and eliminates the possibility of lateral or vertical displacement of the same.
- 10 2) The V-shaped embracing portions or arms are so shaped as to snugly receive all types of drill holders and the vertical slot 59 provides for the proper anchoring relation regardless of variation in size of the drill device and variation in location of the stem member 60.

While I have shown and described the grinding tool as driven by an electric motor, I do not desire to be limited to such driving means since it is obvious that the motive force for actuating the same may take the form of steam or air pressure or any other known motive means.

In adjusting the fixture for operation, the base portion, as a separate part, is first mounted upon the top of the cylinder block as above described. The radial arm 31 is next placed in position upon the base 25, as a separate piece, after which the vertical post 39 with its assembled parts is placed in position upon and within the sleeve 35. The radial arm 31 may then be swung about the bushing 30 toward the cylinder with a compensating rotary movement of the vertical post 39 (and bracket 42) to bring the drive device 23 directly over the cylinder and align the same with the grinding tool to be inserted in such cylinder. Once this adjustment has been effected, the clamp handle 38 is actuated to simultaneously clamp the sleeves 31^a and 35 about their associated mechanisms to lock the same in their adjusted positions for the grinding operation. It will be obvious that with the foregoing compound adjustments, the grinding tool may be moved in a straight line from cylinder to cylinder or moved in any other desired direction to properly and accurately align the same with its driving mechanism and supporting structure. One setting only of the base is all that is required to completely grind all of the cylinders, regardless of their number and regardless of the number of operations to be carried out.

To further adjust the tool 16 for grinding, the handle or lever 51 is moved downwardly moving such tool within the cylinder to the lowest point of the stroke which, preferably, is at a point where the tool projects a slight distance below the cylinder wall, and an adjustable stop 55 carried by post 44 (Fig. 1) is then moved up against the lower part of the sleeve 42^b and clamped in place by its handle 55^a. The lever 51 may then be moved upwardly to the desired height to determine the upper limit of the stroke and another stop

56 carried by the post 44 is moved against the upper part of the sleeve 42^a and secured in place by tightening its adjusting handle 56^a. With these limits definitely established, the grinding tool is inserted in the cylinder and the driving mechanism actuated to revolve the same, the lever 51 being at the same time moved up and down, to grind the cylinder. In grinding a cylinder, roughing stones 17 may be employed in the first operation and all of the cylinders may be "rough ground" before removing the roughing stones; after which smoothing stones are substituted for the roughing stones and all of the cylinders "smooth ground" without removing the smoothing stones.

When using the lever 51 to move the bracket 42, the upper limit of the stroke may be at such a height that the handle 53 of the lever must be moved to a height inconvenient for the operator and, in that event, the handle 53 may be lowered by loosening the clamp screw 49 and sliding the sleeve 46 upwardly along the post 39 to swing the lever 51 about the link 54 is a pivot. The foregoing adjustment of the sleeve structure 46 may also be carried out (with adjustment also of the upper stop 56) to provide for a longer stroke and to vary the upper stroke limit. This latter adjustment may also be employed for the purpose of varying the supporting or cushioning effect of the springs 50 in the case of variation in the weight carried by the bracket 42.

To further increase the speed of operation and reduce the cost of the same and eliminate manual operation, I may reciprocate the bracket 42 and its associated grinding mechanism by mechanical means rather than by the manually operated lever 51. In that case, I may employ a structure such as shown in Figs. 9 and 10 which comprises a gear housing 65 having a depending internally threaded part 65^a engaging the upper threaded end of the standard 39. In that case the cap 41 (Fig. 1) is dispensed with and the liquid added to the reservoir 39^a through any desired form of fill-opening (not shown). The housing 65 carries a worm gear 66 mounted on a shaft 67 which passes through the housing and carries at its opposite ends cranks 68 having dove-tail adjusting slots 69 extending throughout their length. The gear 66 is driven by a worm 70 carried by shaft 71 which is driven by any suitable power means such as an electric motor (not shown). Crank pins 72 are adjustably mounted in the slots of the cranks 68 and one end of links 73 are connected to and freely rotatable upon such pins. The links are provided with a plurality of openings 74 for receiving the crank pins so that such links are adjustable for varying the stroke of the tool bracket 42 to which the other end of these links 73 are pivoted as at 75. In operation, movement

of the gear 66 revolves the crank 68 to reciprocate the bracket 42 and tool 16 in an obvious manner. Adjustment of the crank pins 72 and links 73 as above described determines the proper stroke for each cylinder and, if desired, the bracket 46 and stops 55 and 56 (Fig. 1) may be omitted.

In Figures 11, 12 and 13 I show another manner of clamping the base to the cylinder block. In the form of block 76 shown in Fig. 11, the studs 77 at one side are spaced farther apart than the studs 78 directly opposite. None of the studs are removed to mount the base, and to secure it I employ 10 U-shaped clamp blocks 79 carried by studs 77 and having their ends overlapping the flared flange of the base 25, the nuts 80 tightly securing these parts in that position. The other end of the base is secured by the clamp 15 plate 79^a which in this case passes over the top of the base and engages the opposite studs 78, the nuts 81 tightly securing such clamp plate in the position shown. Or, if 20 cap screws are used to secure the head, they will be passed down through the clamps to engage the proper block openings. It will be noted that the U-shaped clamp plates 79 (Fig. 11) have their ends opposite the base 25 supported by blocks 82 or other suitable 25 devices to exert a more uniform pressure on the base flange. It will also be seen from the foregoing that by making the base 25 fan-shaped, it is readily and quickly adjustable to all types of cylinder blocks in addition to 30 the other advantages to be gained as hereinabove set forth.

From the foregoing it is readily seen that my invention overcomes all the objectionable features in the device heretofore used. The 40 structure is light in weight and may be readily and quickly assembled piece by piece thereby relieving the operator of the burden of assembling the mechanism as an entire unit. The compound radial action enables 45 the operator to easily and quickly align the fixture parts and driving mechanism with the grinding tool and cylinder bore, the double clamping arrangement associated with the radial arm reducing the number of operations in this respect. All of the cylinders 50 may be ground with one setting of the base due to this universal adjustment of the fixture parts thereby speeding up operations and reducing the cost of the same. The labor 55 required to properly grind the cylinders is reduced to a minimum and a plurality of cylinders may be treated to the same identical and exacting degree.

It is to be understood that I do not desire 60 to be limited to the identical constructions disclosed in the drawings because it is obvious that various changes and modifications may be made therein without departing from the spirit and scope of my invention as defined by the claims which follow. If desired,

a drill plate or base may be substituted for the base 25 which has a cylindrical part corresponding to the part 26 and in which the lower part of the upright standard 39 may be directly carried; or such upstanding cylindrical part of the drill plate may receive a fixed bushing corresponding to the bushing 30 to receive in a like manner the radial arm 31 and its associated mechanisms, in which cases a drilling, or other, tool may be substituted for the grinding tool and the fixture used for drilling and similar uses.

I claim:

1. In a cylinder grinding fixture, the combination with a cylinder grinding tool and driving means therefor, of a base adapted to be secured to the cylinder block, a radial arm rotatably adjustable upon said base, a supporting standard rotatably adjustable upon said arm, a bracket slidably and non-rotatably carried by said standard, said driving means being carried by said bracket, and means for securing said arm and standard in any of their rotatable positions.

2. In a cylinder grinding fixture, a base 90 having a vertical shaft part, a horizontal arm swingably adjustable upon and carried by said shaft, a vertical standard carried by and rotatably adjustable relative to said arm, a bracket slidably mounted upon said standard and swingable therewith, a fixed bracket upon said standard, yieldable means for suspending said slideable bracket from said fixed bracket when at rest and an operating lever pivoted to said fixed bracket and connected to said slideable bracket by link means for positively reciprocating said slideable bracket.

3. In a cylinder grinding fixture, a separate base adapted to be mounted upon the 105 cylinder block and having a vertical shaft part, an arm having one end carried by and rotatably adjustable upon said vertical shaft, a vertical post carried by and rotatably adjustable upon the other end of said arm, another vertical post carried by said first post, a bracket slidably mounted upon both said posts and adapted to move with said posts in a rotary direction, and means associated with said posts and bracket for reciprocating 110 said bracket, said bracket being adapted to support driving mechanism for a grinding tool.

4. In a cylinder grinding fixture, a light-weight base adapted to be mounted upon the 120 cylinder block as a separate unit, said base having an upstanding shaft part at one end, an arm mounted upon said vertical shaft as a separate unit and adapted to swing in a horizontal plane, an upright standard swingably mounted upon said arm and a grinding tool supporting bracket slidably mounted on said standard for movement therewith, said standard and bracket being assembled on said 125 arm as a combined and separable unit.

5. In a cylinder grinding fixture, a bracket for removably supporting driving means for a grinding tool, and means for positively positioning said bracket and grinding tool relative to the cylinder to be ground including a base carried by the cylinder block, a radial arm having one end carried by and rotatably adjustable relative to said base, an upright standard having one end carried by and rotatably adjustable relative to the other end of said arm, said bracket being slidably carried by said standard for rotary movement therewith relative to said arm whereby said tool may be moved by relative rotary movement of said parts to any desired position relative to the cylinder to be ground.
6. In a cylinder grinding fixture, a base adapted to be carried by the cylinder block so that its ends project beyond the side edges of said block and having an upstanding cylindrical shaft at one end, a horizontal arm having a split sleeve at each end, the split sleeve at one end being adapted for rotatable engagement with said shaft, an upright post supported upon and rotatably engaging the sleeve on the other end of said arm, grinding tool actuating means associated with said standard, clamping devices associated with the split portions of each of said sleeves and a single clamping screw associated with the clamping devices on both said sleeves for simultaneously securing said arm and said standard in the positions to which they have been respectively rotated.
7. In a cylinder grinding fixture, a base having an upstanding shaft part, a horizontal arm having a sleeve at one end adapted to receive said shaft part, a sleeve on the other end of said arm, an upstanding shaft adjustably carried by said latter sleeve, grinding tool actuating mechanism carried by said shaft, clamp elements carried by each said sleeves, and a single clamp member engaging the clamp elements on both said sleeves for simultaneously securing said arm and associated parts together.
8. A cylinder grinding tool fixture including an arm having split sleeves at opposite ends, clamp elements carried by the split portions of each sleeve, and a single clamp member engaging all said clamp elements for simultaneously drawing the split portions of said sleeve together.
9. A cylinder grinding tool fixture including a fixed vertical shaft, an arm having split sleeves at opposite ends, one of said sleeves receiving said shaft, an upright standard carried by said other sleeve, clamp elements carried by the split portions of each sleeve, and a single clamp member engaging all said clamp elements for simultaneously drawing the split portions of said sleeves together to clamp said shaft and arm and standard together as a rigid unit.
10. A cylinder grinding tool fixture includ-
- ing a base having a vertical shaft post, a horizontal member having sleeves at each end, such sleeves being oppositely split, the sleeve at one end being carried by said shaft part, a vertical standard carried by the other sleeve, grinding tool actuating mechanism associated with said standard, clamp elements carried by each said sleeve, and a single clamp member engaging the clamp element at one end and passing diagonally through said horizontal member and engaging the clamp element at the other end for simultaneously clamping said sleeves about their associated parts.
11. A tool fixture comprising a base, an upright standard adapted for a swinging movement upon said base for movement toward and from the object upon which the tool is to act, said standard being hollow with a closed bottom to provide a cutting fluid reservoir, and a conduit connected to the bottom of said reservoir and having a valve therein for controlling the flow of fluid from said reservoir to said tool and object, and tool actuating mechanism associated with said standard.
12. A cylinder grinding fixture comprising a base, an upright standard adapted for a swinging movement upon said base for movement toward and from the cylinder to be ground, said standard being hollow with a closed bottom to provide a grinding fluid reservoir, and a conduit connected to the bottom of said reservoir and having a valve therein for controlling the flow of fluid from said reservoir to the cylinder being ground, and grinding tool actuating mechanism associated with said standard.
13. In a tool supporting and operating fixture, a base, an upright standard mounted for a swinging movement upon said base, and a bracket slidably carried by said standard for swinging movement therewith and having means for supporting a device for driving the tool, said means comprising pairs of vertically spaced V-shaped arms adapted to embrace a part of said drive device, said arms being held in connected spaced relation by a vertical back part, said back part having a slot for adjustably receiving a part of said drive device for securing the same to said bracket to swing with said standard, and to accommodate drive devices of various sizes and shapes.
14. A tool supporting and operating fixture comprising a base, an upright standard carried by said base, a second upright standard carried by said first standard by spaced brackets, a tool supporting member having spaced arms each slidably engaging both said standards, a control lever having one end pivoted to the upper of said brackets and its other end free, a link pivoted to said lever intermediate its ends and to said member, said upper bracket being vertically adjust-

able along said standard to swing said lever about said link and vary the uppermost position of the free end of said lever and to vary the upper limit of movement of said member.

15. A tool supporting and operating fixture comprising a base, an upright standard adjustably carried by said base, another and spaced upright standard supported by and 10 adjustable with said first-mentioned standard, a tool supporting and actuating member having spaced arms slidably carried by both said standards, means for sliding said member vertically along said standards, an adjustable stop carried by said second-named standard beneath said member and engaged by the lower arm of said member in its lowermost position, and another adjustable stop carried by said second standard and engaged 20 by the upper arm of said member in its uppermost position.

16. A tool supporting and operating fixture comprising a base, an upright standard rotatably carried by said base, another upright standard carried by said first-mentioned standard and rotatable therewith, a tool supporting and actuating member having spaced arms slidably carried by both said standards, means for sliding said member vertically along said standards, and adjustable means carried by said second-named standard for varying the extent of movement of said member and the length of the stroke of the tool.

25 17. A tool supporting and operating fixture comprising a base, an upright standard swingably carried by said base, another upright standard carried by and swingable with said first-mentioned standard, a tool supporting and actuating member having spaced arms slidably carried by both said standards, means for sliding said member vertically along said standards, and adjustable means carried by said second-named standard for varying the upper or lower or both limits 40 of movement of said member.

18. A tool supporting and operating fixture comprising a base, upright tool-supporting standards carried by said base, a tool 50 supporting and actuating member slidably carried by one of said standards, means for sliding said member vertically along said standards, and adjustable means carried by one of said standards for varying the upper or lower or both limits of movement of said member and additional means adjustably carried by one of said standards for independently varying the said upper limit or range of movement of said member.

55 19. A tool fixture comprising a base having an upstanding hollow cylindrical part, a hollow bushing secured in and projecting above said cylindrical part, a horizontal arm having a split sleeve at one end engaging the 60 projecting part of said bushing to permit

said arm to be rotatably adjusted thereupon, means for clamping said sleeve upon said bushing for securing said arm in any of its adjusted positions, a split sleeve at the other end of said arm, an upright post supported by said latter sleeve for rotary adjustment relative thereto, means for clamping said latter sleeve to said post for securing the post in any of its rotary positions, a support for the tool and its actuating mechanism having projecting arms slidably carried by said post, and means for sliding said support along said post.

10 20. In a tool supporting and actuating fixture, a base, an upright post, tool supporting and actuating members carried by said post, and a compound rotary swinging joint between said base and said post, including a radial member swing-connected to both said base and post and clamp means for securing said post and associated parts in any of its swinging positions.

In testimony whereof, I have subscribed my name.
